UNITED STATES PATENT OFFICE.

ALBERT E. PLOWMAN, OF NEW YORK, N. Y.

BUTTON FOR HOSE-SUPPORTERS.

No. 823,628.

Specification of Letters Patent.

Patented Oct. 16, 1906.

Application filed June 26, 1905. Serial No. 267,043.

To all whom it may concern:

Be it known that I, ALBERT E. PLOWMAN, a citizen of the United States, residing at New York, in the county of New York and State of New York, have invented a certain new and useful Improvement in Buttons for Hose-Supporters, of which the following is a full, clear, and exact description.

Various devices have been used to provide a tractive surface upon the button-like head used in connection with a loop in that class of hose-supporters in which the material of the stocking is laid over the head and engaged therewith by the loop, so as to prevent slipping and the abrasion and tearing of the stocking. Durability of the tractive facing itself and also in its application to the head is an essential feature of such devices, and the object of this invention is to secure such durability.

The invention consists of a hose-supporter button having a post and a tractive facing secured to it by a metal clamping member and exposed about the top and side of the post, as I will proceed now particularly to set forth and finally claim.

In the accompanying drawings, illustrating the invention, in the several figures of which like parts are similarly designated, Figure 1 is a perspective view. Fig. 2 shows in perspective the several component parts of the device of Fig. 1 before assembling. Fig. 3 is a longitudinal section of one form of hollow post shown in Fig. 2. Fig. 4 is a longitudinal section of a modified form of button. Fig. 5 shows in perspective the component parts, excepting the base-plate, of the modification Fig. 4. Fig. 6 is a plan view and a cross-section, cupped, of a modified form of clamping member. Fig. 7 is a longitudinal section of a hollow capped post shown in Fig. 5. Fig. 8 is a longitudinal section of a button having a solid post and a clamping member such as shown in Fig. 9. Fig. 9 is a perspective view of the component parts of the button of Fig. 8, excepting the base-plate. Fig. 10 is a side elevation of still another modification. Fig. 11 is a longitudinal section of a solid post shown in Fig. 9. Fig. 12 is a longitudinal section of the modification shown in Fig. 10.

The base-plate 1 is of any approved form and adapted to be applied to the webbing in the usual way. The post 2 may be hollow and open-ended, as in Figs. 2 and 3, and applied to the base-plate before or after the application of the tractive facing 3. This lat-

ter method will especially be used when the metallic clamp, hereinafter described, is applied on the post of the button beneath the head of the post. This tractive facing may be of cloth, leather, rubber, celluloid, or other substance or material which is capable of or may be made capable of yielding under pressure, and it is of larger diameter than the head of the post and is laid over the top of the post and clamped thereon and around the side of the post by a metallic clamping member 4. As shown in Figs. 1 and 2, this clamping member is composed of a central solid portion 5, from which a number of arms 6 radiate, and in applying it the portion 5 is placed over the tractive facing 3 in line with the center of the post and its arms bent down over the rim or side and underneath the head, these arms sinking into the material, so as to cause it to bulge out between the arms and present a series of surfaces over the top and rim or side of the head of the post to which the stocking will adhere in order to prevent its slipping, yet of sufficient softness to obviate abrading and tearing it. The tractive facing may have a central perforation 7, so as to allow the central portion 5 of the clamping member to sink farther into it, as shown at 5^x, Fig. 1, and get into actual or very near contact with the metal of the post. This provision will be of advantage when the tractive facing is applied to the post before the latter is riveted to the base-plate, since the setting-tool is thereby supplied with rigid working surfaces.

Instead of a clamping member having radiate arms there may be used a scalloped disk 8, Fig. 5, having cut out-portions 9 and preferably with the central perforation 10. Such a disk when provided with a central perforation may be slipped upon the post beneath the head of the post before the base-plate 1 is attached to the post and then its rim bent inwardly over the tractive facing, or it may be cupped and applied above the tractive facing and its rim bent inwardly beneath the head. In either case the tractive facing material will bulge out through the openings 9, and that portion of the clamping member adjacent the perforation 7 in the tractive facing will be forced into said perforation, as shown in Fig. 4; or the clamping member may be made of a disk 11, Fig. 6, preferably without a central perforation and having V-shaped cuts 12 near its rim through which the tractive facing bulges, as indicated by the

dotted lines at 12^x in the cross-section, Fig. 6, the disk being cupped, as shown, so as to bring the cuts in the bend for this purpose and applied above the tractive facing in the same manner as the clamping-piece of Fig. 5. In connection with the modifications, Figs. 4, 5, and 6, a hollow post 13, having a capped end 14, such as shown in Figs. 4, 5, and 7, may be used.

10 As seen in Figs. 8 and 9, a radiate clamp 15, having a central perforation 16, may be used, to be applied similarly to the perforated clamp 8 (shown in Fig. 5) beneath the head of the post and its ends turned up and 15 bent inwardly over the tractive facing and their extremities bent down into the central perforation 7 of the tractive facing, as shown at 15^x, Fig. 8. In this modification a solid-headed post 17 is shown.

20 In Figs. 10 and 12 the tractive facing 18 extends over the head and down upon the shank of the post to the base-plate 1, and the arm 6' of the clamping member 4' of a construction similar to that shown in Fig. 2 25 have a similar extent, and thus the entire post, including its shank and head, is provided with a tractive facing exposed beyond the clamping member.

20 Permutations of the different modifications may be used in producing desirable buttons; but in any case the tractive facing is of durable material and is firmly clamped to the post.

If a plastic material is used for the tractive facing, it is matted or knurled to produce a tractive surface and rendered soft before applying, so as to be bent to shape and allow the sinking of the clamping member in it, and afterward hardens, leaving some of its

tractive surface exposed about the top and 40 side of the post beyond the clamping member.

The invention obviously is susceptible of a variety of forms, and there are herein shown and described only those forms which seem best in applying the principle of the invention. 45

What I claim is—

1. A hose-supporter button, having a headed post, a tractive facing of larger diameter than the head of the post applied to said post, and a metallic clamping member applied externally to said facing and causing said tractive facing to be exposed about the top and side of the post beyond said clamping member. 55

2. A hose-supporter button, having a headed post, a tractive facing surrounding the top and rim of the head of the post, and a clamping member applied to the head and sunk in the facing, and causing said facing to be exposed about the top and rim of said head beyond said clamping member.

3. A hose-supporter button, having a post, a tractive facing enveloping the top and side of said post, and a clamping member composed of a central portion and arms radiating therefrom, said clamping member applied to the post and its central portion and arms sunk in the facing, and fastening it to the post and causing said tractive facing to be exposed at the top and side of the post beyond said clamping member. 70

In testimony whereof I have hereunto set my hand this 24th day of June, A. D. 1905.

ALBERT E. PLOWMAN.
